The ornamental design for a plastic tube with application nozzle, as shown.

DESCRIPTION

FIG. 1 is a front perspective view of a plastic tube with application nozzle according to the present invention; FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.
